UNITED STATES PATENT OFFICE.

LEE T. OWENS, OF TACOMA, WASHINGTON.

BRUSH-HOLDER.

1,095,226.

Specification of Letters Patent.

Patented May 5, 1914.

Application filed February 18, 1913. Serial No. 749,079.

To all whom it may concern:

Be it known that I, LEE T. OWENS, a citizen of the United States, and a resident of Tacoma, in the county of Pierce and State 5 of Washington, have invented a new and useful Brush-Holder, of which the following is a specification.

This invention relates to devices by means of which a calcimine brush may be supported in the pail of calcimine when it is not in use, and has for its objects to provide a simple, cheap and effective device which will so support the brush within the pail that the drippings therefrom will 10 fall therein and none of the liquid on the sides or rim of the pail will get on the brush handle, and whereby the handle is always in position to be grasped without having to turn it in the hand, and from which 15 position it is convenient to insert the brush into the calcimine in the pail.

Further objects are to provide a device which will not injure or scratch the wall when the brush is in use, nor in any way 20 interfere with the free use of the brush by the operator.

I attain these and other objects by the devices, forms and arrangements illustrated in the accompanying drawings, in which—

Figure 1 is a vertical section through a pail showing a brush, equipped with my device, sustained therein; Fig. 2 is a longitudinal section of the end portion of a brush showing the method of attaching my device thereto; Fig. 3 is a cross-section thereof; Fig. 4 is a plan of a removable form of my device; and Fig. 5 is a perspective view thereof.

Similar numerals of reference refer to 40 similar parts throughout the several views.

The back of a calcimine or other similar brush, is composed of two pieces of wood, the lower piece 1 carrying the brush bristles 2, and the upper piece 3 being secured to the 45 upper side of the piece 1 by any suitable means. The upper piece 3 carries the brush handle 4 secured at its center and extending therefrom at right angles thereto. Now it is very desirable to keep the handle of such a

brush as free from the calcimine as possible 50 but this is very difficult if the brush has to be laid across the top of the pail or on any support attached to the pail, and I have therefore devised the following described hook or hanger. 55

In the preferred form, this invention is mounted permanently on the brush, being inserted in place during the manufacture of the brush. Two vertical parallel holes 5 are made through the upper part 3, near one 60 end, and a groove 6 joins them in the lower face of the said piece. A piece of heavy wire 7 lies within the groove 6 and its ends turn up and pass through the holes 5 from which they emerge forming two parallel 65 uprights 8 which extend a short distance above the level of the piece 3; the parts 8 are then bent toward the adjacent end of the brush, forming two horizontal parts 9, which in turn are bent down to form two short 70 hooks 10. The length of the parts 9 is such that the hooks 10 are almost over the edge of the brush, but do not quite reach that far.

In the removable form, shown in Figs. 4 75 and 5, I have provided a device which can be applied to brushes which have not been equipped at the factory as above described. This consists of a wire loop 11 adapted to lie on the upper surface of the part 3, and 80 having its ends bent to correspond with the above described parts 8, 9 and 10; while two clips 12 are permanently secured to the ends of the loop 11, said clips extending sideways to the edge of the brush and then 85 being bent downward and then having inward extending teeth 13 adapted to be pressed into the wood of the part 3, thus securing the device to the brush. It is evident that this piece can be readily applied to any 90 brush which it will fit over and can be as readily removed therefrom.

Having described my invention, what I claim is:—

1. A brush holder comprising a pair of 95 parallel legs of substantially L-form secured to the brush and having hooks formed at their terminals, means for securing the

holder to the brush whereby the hook terminals lie side by side within the area of the brush back and over one end of the same.

2. A brush holder comprising a single strand of spring wire bent to form a spring loop and substantially parallel legs having hooks on their terminals and clips connected to opposite legs and adapted to be drawn

into engagement with the sides of the brush back for securing the holder in position 10 thereon.

LEE T. OWENS.
